CLAIM

The ornamental design for an orthopaedic bone plate, as shown and described.

DESCRIPTION

FIG. 1 is a top perspective view of an orthopaedic bone plate showing the present design.

FIG. 2 is a bottom perspective view thereof.

FIG. 3 is a top view thereof.

FIG. 4 is a bottom view thereof.

FIG. 5 is a left side elevational view thereof.

FIG. 6 is a right side elevational view thereof.

FIG. 7 is a front view thereof showing one end of the present invention.

FIG. 8 is a rear view of the invention shown in FIG. 5.

FIG. 9 is a top perspective view of second embodiment of the present invention.

FIG. 10 is a bottom perspective view thereof.

FIG. 11 is a top view thereof.

FIG. 12 is a bottom view thereof.

FIG. 13 is a partial front elevational view thereof.

FIG. 14 is a rear elevational view thereof.

FIG. 15 is a right side elevational view thereof; and,

FIG. 16 is a left side elevational view thereof.

The broken line showing is for illustrative purposes only and forms no part of the claimed design.
